UNITED STATES PATENT OFFICE.

FREEMAN M. W. BURHOE, OF NORTHRIDGE, MASSACHUSETTS.

AUTOMATIC SPRINKLER.

1,118,266.

Specification of Letters Patent. Patented Nov. 24, 1914.

Application filed May 27, 1914. Serial No. 841,287.

To all whom it may concern:

Be it known that I, FREEMAN M. W. BURHOE, a citizen of the United States, residing at Northbridge, in the county of Worcester 5 and State of Massachusetts, have invented a new and useful Automatic Sprinkler, of which the following is a specification.

The present invention appertains to automatic sprinklers or fire extinguishers, and 10 aims to provide a novel and improved sprinkler head for use in fire extinguishing apparatus.

The present invention contemplates the provision of a sprinkler head including a 15 discharge nozzle, a combination valve and deflector or spreader, and a unique means for normally maintaining the valve seated upon the nozzle to close the same, and for enabling the valve and deflector to be 20 thrown open, under the pressure of the water or fire extinguishing agent, when the said means is released, in order that the spreader or deflector will serve to spread the water over a comparatively large area.

Another object of the present invention 25 is to provide a device of the nature indicated, which may be compactly folded together, when the valve is seated against the nozzle, to hold the valve seated, and to enable the valve holding means to be held in 30 place by means of suitable fusible material, the structure being comparatively simple, compact and inexpensive in construction, as well as being simple, practical and efficient 35 in operation.

With the foregoing and other objects in view which will appear as the description 40 proceeds, the invention resides in the combination and arrangement of parts and in the details of construction hereinafter described and claimed, it being understood that 45 changes in the precise embodiment of the invention herein disclosed can be made within the scope of what is claimed without departing from the spirit of the invention.

The invention has been illustrated in its preferred embodiment in the accompanying drawing, wherein—

Figure 1 is a sectional view of the sprinkler head in closed condition. Fig. 2 is a 50 plan view of the sprinkler head in closed condition. Fig. 3 is a side elevation of the device in open condition.

The improved sprinkler head embodies a 55 body 1, which may be square, or of any other suitable contour, and which is tubu-

lar or hollow. The lower end portion of the body 1 is formed into a nipple 2 to engage downwardly within the top of the sprinkling pipe, as is usual in devices of this character. The body 1 further includes an upstanding nozzle portion 3, the upper end of which forms a valve seat. The body 1 of the sprinkler head is formed at opposite sides with diverging upwardly curved arms 4 and 5, which project above the upper end of the nozzle 3.

A link 6 has a bifurcated end 7 pivoted over the upper end of the arm 4, by means of a rivet or other pivot member 8, in order that the outer or free end of the link 6 may swing to and from the arm 5 over the nozzle 3. The link 6 is provided at its free end, with a tongue 9 of reduced width, adapted to enter a kerf or slot 10 formed in the upper end of the arm 5, when the link is swung downwardly, as seen in Fig. 1.

There is provided a valve 11 seatable upon the upper end of the nozzle 3, and preferably having a boss 12 engageable within the nozzle 3, to insure of the perfect closure of the nozzle 3, when the valve 11 is seated. That face of the valve 11, opposite the boss 12, is formed with a spreader or deflector 13, which preferably has a scalloped rim. The valve 11 is carried by the free end portion of the link 6, and to this end, the valve is provided with a radial bifurcated projection 14 straddling the link 6 adjacent the tongue 9 or the free end of the link, and pivoted thereto by means of a rivet or other member 15. A pin or rivet 16 is engaged through the arms or branches of the bifurcated portion 14, and is engageable with the link 6 to serve as a stop, as seen in Fig. 3, when the link and valve 11 have swung upwardly to open position.

The arm 4 of the sprinkler head body is provided with an upstanding stop or lug 17 at its upper or free end, against which the link 6 is arranged to strike, when the link swings to erect position, as seen in Fig. 3.

In order to assist in the unseating or opening of the valve 11, a coiled wire spring 18 surrounds the nozzle 3 and seats upon the body 1 of the sprinkler head, and this spring 18 is adapted to be compressed when the valve 11 is seated, as seen in Fig. 1.

As a means for swinging the valve 11 away from the link 6, the link is provided at that side adjacent the valve, with a recess 19, in which a flat spring 20 is secured, the

spring 20 having a flexible or resilient leaf 21 coöperable with the valve 11. Thus, when the valve 11 is swung against the link 6, the leaf 21 is arranged to be swung back into the recess 19 by the valve, and when the valve is released, the spring leaf 21 will spring away from the link 6, to thereby throw or force the valve 11 away from the link.

10 The parts are so arranged, that when the valve 11 is swung against the inner side of the link 6, the spring leaf 21 being swung within the recess 19, and when the link is swung downwardly so that its tongue 9 engages the slot or kerf 10 of the arm 5, the valve 11 will be seated tightly upon the nozzle 3, the link 6 and its spring 20 bearing upon the upper or outer surface of the valve 11, or the deflector or spreader 13 of the valve, to hold the valve seated. The valve being seated will compress the spring 18. The parts are held in this closed position, by means of solder or other fusible material 22 which binds or secures the free end of the link 6 to the arm 5, under ordinary conditions. Thus, the solder or fusible material 22 will resist the upward movement of the link 6, under the water pressure against the valve 11, under ordinary conditions, but 25 should the solder or fusible material 22 become heated to an abnormal degree, such as is caused by conflagration, the solder or material 22 being fused, will release the link 6 so that the link 6 may be thrown upwardly by reason of the water tossing the valve 11 upwardly. The spring 18 also assists in unseating the valve, should the valve stick. Thus, when the valve 11 is opened, due to the releasing of the link 6, the link 6 will 30 be swung to erect position, and the valve 11 will be thrown from the link by the spring 20 and will be reversed or turned upside down, with the pin or stop 16 engaging the link 6, to prevent the excessive upward movement of the valve 11 and the deflector or spreader 13 carried thereby. In this manner, the spreader or deflector 13 will be brought into operation, and will lie directly in the path of the stream of water issuing 35 from the nozzle 3, so that the water will be spread or deflected radially in all directions to extinguish the adjoining conflagration.

The present device may be readily reset, to close the passage through the body and nozzle, as seen in Fig. 1, and as will be obvious without further description.

The present device may be, and preferably is, operated in an upright position, but may be operated in other positions as well. When 40 the parts are folded, as seen in Fig. 1, to close the valve, the parts will be protected, more or less, and the tendency or accidental breakage of the parts, will be reduced to a minimum. The sprinkler head is of such 45 simple construction, that there will be no

tendency to impair the flow of water through the sprinkler head, when the valve 11 is opened, whereby the friction of the water through the head will be reduced to a minimum, to increase the spreading action of 70 the water when the water impinges against the spreader or deflector 13. The present device is a reliable and simple one, and is of advantage in other obvious respects, which will need no further comment.

Having thus described the invention, what is claimed as new is:

1. A sprinkler head including a nozzle, a valve seatable at one side against the nozzle and having a spreader at its other side, 80 and means for mounting the valve to seat the same against the nozzle and to reverse the valve when forced away from the same.

2. A sprinkler head including a nozzle, and a valve seatable against the nozzle and being arranged to be reversed when forced away from the nozzle, the valve having a spreader on its reverse side.

3. A sprinkler head including a nozzle, a link swingable to and from the same, and a valve pivoted to the link having one side seatable against the nozzle, the other side of the nozzle being provided with a spreader.

4. A sprinkler head including a body having a nozzle and having opposite arms, a link pivoted to one arm and adapted to be detachably secured to the other over the nozzle, and a valve pivoted to the link having one side seatable upon the nozzle when the link is attached to the second mentioned arm, the other side of the valve having a spreader and being engageable by the link when the valve is seated.

5. In a sprinkler head, a nozzle, a pivoted link arranged to swing to and from the nozzle, means for limiting the movement of the link away from the nozzle, a valve pivoted to the link and having one side seatable against the nozzle, the other side of the valve having a spreader, and means for limiting the movement of the valve relative to the link.

6. In a sprinkler head, a body having a nozzle and having opposite arms, a link having one end pivoted to one of the said arms, the link and said arm having means for limiting the movement of the link when swung away from the nozzle, the free end of the link being attachable to the other arm over the nozzle, a valve pivoted to the free portion of the link and having one side seatable against the nozzle, the other side of the valve having a spreader, and means for limiting the movement of the valve relative to the link when the link is swung away from the nozzle.

7. A sprinkler head including a body having a nozzle, a link pivoted to the body, a valve pivoted to the link and having one side seatable against the nozzle, the other side

side of the valve being provided with a spreader, and a coiled wire spring surrounding the nozzle and seated on the body for raising the valve.

5 8. A sprinkler head including a nozzle, a link swingable to and from the nozzle, a valve pivoted to the link and having one side seatable against the nozzle, the other side of the valve being provided with a 10 spreader, and a spring carried by the link.

and coöperable with the valve for swinging the valve away from the link.

In testimony that I claim the foregoing as my own, I have hereto affixed my signature in the presence of two witnesses.

FREEMAN M. W. BURHOE.
